UNITED STATES PATENT OFFICE.

NICOLAS TALARD, OF PARIS, FRANCE.

PUMP.

SPECIFICATION forming part of Letters Patent No. 251,967, dated January 3, 1882.

Application filed May 7, 1881. (No model.) Patented in France December 30, 1876, and in England December 7, 1880.

To all whom it may concern:

Be it known that I, NICOLAS TALARD, a citizen of France, residing at Paris, in the Republic of France, have invented a new and useful improved construction of pumps for exhausting, raising, or forcing air and other fluids, (for which I have obtained a patent in Great Britain, No. 5,103, bearing date December 7, 1880, and in France, bearing date December 10, 1876,) of which the following is a specification.

My invention relates to an improved construction of pumps, more particularly applicable to the exhausting of air and gases from receivers for sewage matters, such as described in my application for Letters Patent filed on the 23d February, 1881, but which is also applicable for exhausting air and other gases or fluids generally. The construction of the said 20 pump will be readily understood on reference to the accompanying drawings, in which—

Figure 1 shows a longitudinal section of the pump-barrel; Fig. 2, an end view of the same; and Fig. 3 an end view with the cover removed, showing one of the valve-plates and valves.

B is a cylindrical barrel, in which works a piston of ordinary construction, (not shown on the drawings,) whose rod passes through the stuffing-box in the one cover, G. The ends of 30 the cylinder have fitted to them plates K K, in which are openings having suction-valves I I and discharge-valves I' I'. These valves are by preference metal flap-valves faced with caoutchouc, leather, or the like, and they are kept down on their seats by light springs p, coiled round the hinge-pin of the valve, and bearing with a loop, p'', upon the valve, while the ends p' bear against the plate K. Over the valve-plates are fitted the hollow covers 35 G G, having cross-ribs G' fitting air-tight against the plates K, so as to form two separate chambers in each cover, the one communicating with the suction-valves I and the other with the delivery-valves I'. These valves are loosely pivoted at their upper portions on the hinge-pins before referred to, which pins are secured in horizontal positions on the inner and outer sides of the plates K, as shown, and by this arrangement and the action of 40 the coiled springs there is no liability of the valves becoming obstructed or failing to properly perform their work. It should be ob-

served that the longitudinal passages h h and central lateral branches, H H, are formed integral with the cylinder B, whereby the construction of the pump is simplified and the cost of production reduced. The hollow covers G G form perfectly closed ends to the pump, and the two chambers formed by the cross-ribs G' communicate respectively with two longitudinal passages, h h, formed through the sides of the cylinder B, which passages have at their middle branches H H, that are connected by means of sockets i i, respectively, with the suction and delivery pipes B' B''. The covers and valve-plates are all secured air-tight to the ends of the cylinder, by preference, by means of one set of screw-bolts, F', passing through holes in flanges F on the ends of the cylinder and through corresponding holes in the covers and valve-plates.

I am aware that a pump has been composed of a cylinder having suction and discharge valves in its ends, with two separate pipes, placed one on each side of the cylinder, and connected at their ends to hollow boxes divided into two chambers by a partition, said hollow boxes being provided respectively with inlet and outlet orifices formed in line with the before-mentioned pipes; but such construction of parts is not my invention.

I claim as my invention—

1. In a pump for the purpose described, the cylinder B, formed integral with the longitudinal passages h h, which are provided intermediate of their ends with laterally-projecting inlet and outlet branches H H, in combination with the hollow covers forming closed ends to the pump, and valve-plates applied to the ends of the cylinder, and provided with suction and discharge valves, substantially as described.

2. In a pump for the purposes described, the cylinder B, formed integral with the longitudinal passages h h, which are provided intermediate of their ends with the laterally-projecting inlet and outlet branches H H, in combination with the hollow covers forming closed ends to the pump, and each divided into two chambers, and the plates K, attached to the ends of the cylinder and provided with valves I I', pivoted in position and acted on by springs, all substantially as shown and described.

3. In a pump for the purposes set forth, the cylinder B, having within it the longitudinal

passages *h h*, provided with laterally-projecting inlet and outlet branches *H H*, in combination with the two hollow covers *G G*, having ribs *G'*, the valve-plates *K*, provided with 5 horizontal hinge-pins, the valves *I I'*, loosely pivoted on said hinge-pins, and springs acting on said valves, substantially as shown and described.

In testimony whereof I have signed my name to this specification, in the presence of two sub-¹⁰scribing witnesses, this 15th day of April, A. D. 1881.

NICOLAS TALARD.
